UNITED STATES PATENT OFFICE

99,423

DESIGN FOR A SPORT GLOVE

Laura K. H. Thomsen, Alameda, Calif.

Application December 6, 1935, Serial No. 59,944

Term of patent 14 years

To all whom it may concern:

Be it known that I, Laura K. H. Thomsen, a subject of the King of Denmark, and a resident of the city of Alameda, county of Alameda, State of California, have invented a new, original, and ornamental Design for a Sport Glove, of which the following is a specification, reference being had to the accompanying drawing, forming a part thereof.

In the drawing:

Fig. 1 is a plan view of the front of the glove shown open and embodying the design;

Fig. 2 is a plan view, slightly in perspective, of the front of the glove disclosed in Fig. 1, shown fastened, the fingers of the glove being broken away;

Fig. 3 is a plan perspective view of the back of the glove disclosed in Fig. 1 and shown fastened, the fingers and thumb being broken away.

I claim:

The ornamental design for a sport glove substantially as shown and described.

In testimony whereof, I have hereunto set my hand this 2nd day of December, 1935, at San Francisco, California.

LAURA K. H. THOMSEN.
